Primary Examiner—Philip S Hyder*Assistant Examiner*—Roselynne Cody*(74) Attorney, Agent, or Firm*—Salter & Michaelson(57) **CLAIM**

The ornamental design for a jewelry box, as shown and described.

DESCRIPTION

FIG. 1 is a perspective view of the jewelry box of the present invention showing the supported items and a cord in phantom;

FIG. 2 is a perspective view of the jewelry box without the supported items and the cord;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a perspective view of the jewelry box open; and,

FIG. 10 is a perspective view of the jewelry box with a part removed.

The broken lines in FIG. 1 are directed to environment only and form no part of the claimed design.
